(57) **CLAIM**

The ornamental design for a peg for a hook, as shown and described.

DESCRIPTION

FIG. 1 is a rear elevation view of a peg for a hook shown in accordance with my new design;

FIG. 2 is a left side elevation view thereof;

FIG. 3 is a front elevation view thereof;

FIG. 4 is a right side elevation view thereof;

FIG. 5 is a top plan view thereof;

FIG. 6 is a bottom plan view thereof; and,

FIG. 7 is a rear perspective view thereof.

The features shown in broken lines form no part of the claimed design.
